UNITED STATES PATENT OFFICE.

LEON A. STORZ, OF WORCESTER, MASSACHUSETTS.

CASTING MACHINE.

Application filed November 1, 1920. Serial No. 421,120.

To all whom it may concern:

Be it known that I, LEON A. STORZ, a citizen of the United States, residing at Worcester, in the county of Worcester and Commonwealth of Massachusetts, have invented a new and useful Improvement in a Casting Machine, of which the following, together with the accompanying drawings, is a specification.

10 My invention relates to metal casting machines, particularly of the type employed by dentists for the casting of inlays, bridges, plates, and the like, in which a source of pressure is employed in connection with the casting operation to force the molten metal into the mold. It is to be understood, however, that my machine is capable of application to other classes of work which may require the formation of relatively small metal 20 castings.

In my copending application Serial No. 379,296, filed May 6, 1920, there is shown and described a casting machine of the above mentioned type, in which a vertically movable flask containing a mold is adapted to operate a valve mechanism located above the flask. The valve mechanism controls the flow of fuel and pressure mediums through a nozzle in the direction of the flask, so that the metal which is to be cast is first melted and then subjected to pressure.

The object of the present invention is to provide a casting machine embodying the essential elements of the machine described in the above mentioned copending application with certain improvements, whereby its effectiveness in operation is greatly increased. My improved machine is also universal in its application, in that it may utilize any available sources of fuel and pressure in various combinations without necessitating any changes in its general arrangement. These and other advantageous features of my invention will hereinafter more fully appear, reference being had to the accompanying drawings, in which—

Fig. 1 is a view, partially in section, of my improved casting machine.

50 Fig. 2 is a sectional view along the line 2—2 of Fig. 1.

Fig. 3 is a sectional view similar to Fig. 2, showing the machine connected for operation with a different fuel supply from that shown in Fig. 2.

Like reference characters refer to like parts in the different figures.

Referring to the drawings, the machine generally comprises a base 1 provided with an upwardly extending standard 2, which 60 terminates in a cylindrical portion 3 overhanging the base 1. A cylinder 4 is mounted on the base 1 and a piston 5 is adapted to operate therein. A plunger 6 is connected to the piston 5 at its lower end and at its 65 upper end extends through the top of the cylinder 4, where it is connected to a casting table 7. The table 7 is provided with a number of concentric depressions or seats 8, within one of which is received a hollow 70 cylindrical flask 9. The flask 9 is filled with investment material 10, and a mold, as indicated at 11, is formed therein by any suitable means. A convex depression 12 is provided in the material 10 and is in communication with the mold 11 through a sprue-way 13. A quantity of metal 14 is located 75 in the depression 12 and is adapted to be melted by instrumentalities which will be hereinafter described.

80 The inner wall of the flask 9 is provided with a peripheral groove 15, into which the investment material 10 enters when it is placed in the flask 9. The bottom of the flask 9 is provided with a plurality of openings 16, which are in communication with an axial and radial passage 17 provided in the plunger 6. The functions of the groove 15 and of the openings 16 during the operation of the machine will be hereinafter more 85 fully described.

85 The cylinder 4 is provided at its ends with ports 18 and 19 which are connected by piping to a suitable two-way valve 20. The valve 20 may be of any usual construction, so that its inlet port 21 will be connected to one port 18 of the cylinder 4 when its exhaust port 22 is connected to the other port 19 of the cylinder 4, and vice versa. The inlet port 21 of the valve 20 is connected to a suitable source of air under pressure through a suitable air filter, as indicated at 23. The filter 23 may be of any usual type in which air under pressure is forced to pass through some material which removes the moisture therefrom, provision being made for the removal of the moisture by means of a pet-cock 24.

100 With the valve 20 in the position shown, the piston 5 is adapted to be held at the 110

lower end of the cylinder 4, but it is obvious that should the valve 20 be turned through an angle of 90°, air under pressure will be admitted through the port 19 and thereby cause the casting table 7 to be raised into engagement with the valve mechanism, which will now be described.

As best shown in Fig. 2, the cylindrical portion 3 of the standard 2 is provided with a central longitudinal opening 25, within which valve members 26 and 27 are adapted to slide. The upper valve member 26 is provided with a central passage 28, which communicates with a radial passage 29 extending to the outer periphery of the valve member. A pipe 30, terminating in a restricted opening or jet 31, is secured in the passage 28 and extends downwardly from the valve member 26 into a central opening 32 provided in the lower valve member 27, the opening 32 being considerably larger in diameter than the pipe 30, for a purpose to be hereinafter described.

The upper valve member 26 is further provided with spaced peripheral grooves 33 and 34 that are adapted to seat a ball 35, forced inwardly toward the member 26 by means of a spring 36. When the ball 35 is seated in the lower groove 34, the valve member 26 is maintained in the position shown in Fig. 1. The valve member 26 is also provided with an enlarged head 37, by means of which the member 26 may be depressed until the ball 35 is seated in the upper groove 33. When the valve member 26 is depressed, the radial passage 29 is brought into register with a port 38 to which is connected a supply pipe 39. The supply pipe 39 is connected to a suitable source of fuel under pressure, which, as indicated in Fig. 1, may be a tank 40 mounted on the base 1. The tank 40 may contain suitable combustible gas such, for example, as oxygen, under considerable pressure, which may be used in combination with another combustible gas such as ordinary illuminating gas, not under an appreciable pressure, by connecting both sources to the pipe 39, as indicated in Fig. 1. A suitable valve 41 is provided at the top of the tank 40 for controlling the flow of the pressure medium to the supply pipe 39.

The lower valve member 27 is provided at its lower end with a plate 42 having a plurality of concentric packing rings 43, which correspond in diameter to the seats 8 provided in the casting table 7. A spring 44 surrounds the valve member between the plate 42 and the end of the cylindrical portion 3, and maintains an enlarged portion 45 of the valve member in engagement with a shoulder 46 provided on the cylindrical portion 3. The plate 42 is provided with upwardly extending stops 47 which are adapted to limit

the upward travel of the valve member 27 within the opening 25, so as to cause a radial passage 48, communicating with the opening 32, to register with a port 49 provided in the cylindrical portion 3. The port 49 is connected to a supply pipe 50 which, as best shown in Fig. 1, is connected to a source of air under pressure above the valve 20.

Having thus described the various parts entering into my invention, the operation thereof is as follows:—The mold 11 having been formed in the flask 9 in any suitable manner, a sufficient quantity of metal 14 is then placed in the depression 12 and the flask 9 is positioned on the table 7. The head 37 of the upper valve member 26 is then depressed, thus bringing the pipe 30 into communication with the source of fuel under pressure, the valve member 26 being held in this position by the ball 35 engaging in the groove 33. The gases are thoroughly mixed in the pipes 30 and 39 before passing through the jet 31 where they are ignited. The metal 14 is heated by the flame thus produced until it reaches the desired molten condition preparatory to forming the casting. The amount of heat to which the metal is subjected is readily controllable by raising or lowering the table 7 through manipulation of the valve 20. When the metal 14 has reached the desired molten state, the valve 20 is operated to cause the piston 5 to be moved upwardly to the end of its stroke, thereby raising the flask 9 until the top engages the plate 42. Continued upward movement of the table 7 causes the lower valve member 27 to be moved upwardly until the stops 47 engage the bottom of the cylindrical portion 3. The upper valve member 26 moves with the lower valve member, thereby causing the radial passage 29 to be moved out of register with the port 38. This immediately cuts off the flame at the jet 31, and at almost the same instant, the radial passage 48 registers with the port 49, thereby admitting air under pressure to the opening 32 surrounding the flame pipe 30. The molten metal 14 is then subjected to pressure over substantially its entire surface and is forced through the sprue-way 13 into the mold 11. The pressure is held between the plate 42 and the upper edge of the flask 9 by means of one of the packing rings 43, which is pressed against the flask by means of the spring 44, the other packing rings 43 providing a seal when flasks of greater or of less diameter are employed. The metal 14 is subjected to pressure for a sufficient time to allow the casting to form within the mold 11. During the casting operation the entire top surface of the investment material 10 is subjected to pressure so that a certain amount of air finds its way through

- the porous material. The openings 16 in the bottom of the flask 9 provide a large number of outlets for the air to the passage 17 in the plunger 6, so that there is no tendency for the investment material to be moved within the flask 9, due to excessive air pressure. This might otherwise occur were the bottom of the flask to be provided with a single opening as in previous constructions. The groove 15 also provides a secure anchor for the investment material, so that there is but little chance of the mold 11 being spoiled by movement of the investment material during the casting operation.
- 15 After the casting is complete, the table 7 is lowered by admitting air to the upper port 18 of the cylinder 4 so that the flask may be removed. The lowering of the table 7 permits the spring 44 to move the valve member 27 to its lower position, thereby cutting off the pressure. The valve member 26 is normally held in its upper position with the fuel shut off by the ball 35 seated in the lower groove 34.
- 20 My improved machine is readily adapted for operation where fuel only under ordinary pressure is available by a very simple change, illustrated in Fig. 3. A casing 51, of greater inside diameter than the pipe 50, is secured in a countersunk portion 52 of the passage 28 in the valve member 26. The casing 51 extends downwardly into the opening 32 in the lower valve member 27 and is constructed at its lower end, as shown at 53, to partially inclose the jet 31, a space being left between the end of the casing 51 and the tip of the jet. A radial duct 54 communicates with the countersunk portion 52 and is adapted to register with a port 55 when the valve member 26 is depressed to seat the ball 35 in the upper groove 33. A pipe 56 leads from the port 55 to a suitable source of fuel under ordinary pressure. The pipe 39, leading from the port 38, is connected to a source of air under pressure, so that when the valve member 26 is depressed, the air discharging from the jet 31 will draw the fuel through the casing 51. When the fuel is ignited, the device will operate as a blow-torch to project an intense flame in the direction of the flask 9. The pipe 50 is connected to a source of air under pressure as before, and the operation of the machine is substantially the same as described with reference to Fig. 2.
- 25 From the foregoing, it is apparent that I have provided an improved casting machine that is adapted to successfully operate with different combinations of fuel mediums, without necessitating any material changes in the parts of the machine. My machine is also extremely effective in its operation, owing to the provision of the pressure operated casting table. It is possible to maintain the flask any desired distance from the source of the flame while the metal is being melted and to hold the flask in contact with the plate 42 with a steady pressure during the casting operation. The provision of a relatively large free opening in the lower valve member through which the pressure is applied to the flask, insures that a considerable area of the molten metal will be exposed to the pressure. This prevents the molten metal from being blown out of the depression 12 as might readily occur should the pressure medium be discharged through a restricted opening, such as the jet 31. The provision of a plurality of openings at the bottom of the flask permits the ready relief of the air which finds its way through the investment material, without any tendency for the material to be moved within the flask.
- 30 While I have shown my present invention embodied in a casting machine operated on the same general principles as the machine described in my above described copending application, it is not so limited, but its several features may be as well embodied in other types of casting machines. I desire therefore that only such limitations be imposed thereon as come within the scope of the appended claims.
- 35 I claim:
1. In a machine of the class described, the combination with a standard carrying a valve mechanism and a vertically movable flask located below said valve mechanism for receiving a mold, of fluid pressure operated means for moving the flask in the direction of the valve mechanism to operate said mechanism.
  2. In a machine of the class described, the combination with a standard carrying a valve mechanism, of a casting table mounted on a pressure operated piston movable within a cylinder located below the valve mechanism.
  3. In a machine of the class described, the combination with a source of pressure and a standard carrying a valve mechanism, of a casting table mounted on a piston movable within a cylinder located below the valve mechanism, and means for controlling the movement of the piston within the cylinder by its connection to said pressure source.
  4. In a machine of the class described, the combination with a casting table mounted on a plunger connected to a piston movable within a closed cylinder, of a flask carried on said table and adapted to be subjected to a pressure medium, the said flask and the said plunger being provided with openings for the escape of the pressure medium from said flask when the said flask is in its upper position.
  5. In a machine of the class described, the combination with a casting table mounted on a plunger connected to a piston movable

- within a cylinder, and a valve mechanism for controlling the flow of a pressure medium in the direction of said table, of a flask carried on said table and adapted to be subjected to the pressure medium upon operation of said valve mechanism by movement of said table, the bottom of said flask being provided with openings, and the said plunger being provided with a duct for the escape of the pressure medium from said flask when the piston is near the top of said cylinder.
6. In a machine of the class described, the combination with a movable table, a source of fuel and a source of pressure, of a valve mechanism comprising valve members relatively movable in the same direction as said table and provided with coaxial passages for the separate flow of fuel and pressure mediums in the direction of said table.
7. In a machine of the class described, the combination with a movable table, a source of fuel and a source of pressure, of a valve mechanism comprising relatively movable valve members, one of which is provided with a passage having a restricted opening for the discharge of fuel medium from said source and the other of which is provided with a passage having a free opening for the discharge of pressure medium from said source in the direction of said table.
8. In a machine of the class described, the combination with a movable table, a source of fuel and a source of pressure, of a valve mechanism operable by the movement of said table and comprising a valve member provided with a passage having a restricted opening for connection to the source of fuel and another valve member provided with a passage having a free opening for connection to the source of pressure.
9. In a machine of the class described, the combination with a movable table, a source of fuel and a source of pressure, of a valve mechanism operable by movement of said table and comprising a valve member having a constricted passage for connection to said source of fuel, and another valve member having a passage of substantially the same cross section throughout its length for connection to said source of pressure, the said passages being coaxial.
10. In a machine of the class described, the combination with a vertically movable flask for receiving a mold, a source of fuel and a source of pressure, of a valve mechanism connected to said sources and adapted to discharge fuel medium through a constricted passage and to discharge pressure medium through a free passage in the direction of said flask.
11. In a machine of the class described, the combination with a vertically movable flask for receiving a mold, a source of fuel and a source of pressure, of a valve mechanism connected to said sources and comprising a valve member provided with a pipe terminating in a restricted opening for the discharge of fuel medium and another valve member provided with a free passage for the discharge of pressure medium.

LEON A. STORZ.
